UNITED STATES PATENT OFFICE.

PAUL TATZ, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

COUPLING BETWEEN RADIO APPARATUS AND HIGH-TENSION TRANSMISSION LINE.

Application filed December 8, 1924, Serial No. 754,480, and in Germany December 18, 1923.

My invention relates generally to the art of using radio frequency signalling current on existing high tension power transmission lines and more specifically to means for coupling 5 the signalling apparatus to the transmission line.

It has for its object to provide a coupling between the radio signalling apparatus and the transmission line which will offer minimum 10 impedance to signalling currents and yet will not interfere with the operation of the transmission line from a power standpoint.

Other objects will be apparent from the following specification and claims considered in connection with the drawings in which;

Figure 1 represents an embodiment of my invention,

Figure 2 represents another form of my invention,

Figure 3 represents a modified form of my invention.

In the use of carrier frequency telephony over high tension transmission lines there is some difficulty in suitably coupling the radio frequency apparatus to the transmission lines. If it is remembered that transmission lines represent ideal conditions with regard to damping, it is obvious that considerable 30 ranges can be attained by means of very small energies, provided, the coupling is suitably adjusted.

Up till now two methods of coupling, which are different in their principles, were employed. The simplest arrangement was obtained by connecting the radio frequency apparatus across high tension condensers directly to the transmission lines, this expedient taking advantage of the considerable difference 40 in impedance of the condensers with regard to high frequency and low frequency.

In order to avoid special coupling condensers, one soon came upon the idea of employing the normal arrangements of high tension buildings for this purpose by insulating the suitable apparatus from earth and utilizing their capacities with regard to earth for coupling purposes and by using the earth as return conductor. This method was, for instance, employed using the high tension wall bushings or ducts. As the disturbing capacity with regard to earth could not be eliminated in practice, this method has been almost abandoned.

For transmission lines of low and medium

voltage the coupling by means of condensers could always be successfully used, as the high tension condensers had relatively large capacities, in comparison with which the disturbing capacity of the arrangements of the 60 high tension buildings was of no great importance.

The conditions are different for very high voltages. One tried to overcome the difficulties by using aerials which were arranged 65 in parallel to the transmission lines and fastened on the same or special masts. Also in this case one soon came upon the idea of utilizing the already existing arrangements of the transmission lines, as, for instance, lighting-conductor cables, for this purpose.

It was now found in practice that nothing could be attained by a short aerial; it was necessary to use aerials of more than 500 meters in length, that is, lengths which correspond to that wavelength which is usually employed for the carrier frequency. These carrier frequencies may not, as known, be too low in order to avoid difficulties, for instance, in the solution of the problem of bridging over 80 disconnecting switches.

The last mentioned fact caused new difficulties. If the relation of the transmission of radio frequency upon the frequency is tested by means of a certain aerial arrangement at 85 both ends of the transmission line, distinct maxima and minima are found which could not be explained by the different qualities, that is, natural frequencies of the transmission line. It is impossible that the characteristic 90 curve of the transmission line could show such great differences.

It was, for instance, found that one coupling wire oscillating on one wavelength is not adapted for transfer of energy. Practice 95 shows plainly that there are certain favorable carrier frequencies particularly due to the qualities of the coupling wires and not to those of the transmission line. Consequently the length of the provided coupling wire pre-determines certain carrier frequencies. On the other hand, it is not possible to use coupling wires of equal length (for instance, in employing lightning conductor cables) for transmission lines with several radio frequency telephony arrangements. Therefore, it is obvious, that the problem of coupling up till now caused great difficulties for arrangements of very high tension.

These difficulties are overcome by the pres- 110

ent invention, which is based upon the fact that the generation of stationary oscillations is prevented in a known manner by suppressing the reflection of the waves by absorbing them by suitable resistances. In case of 5 horizontal linear systems of conductors, the result is attained that the waves can be transferred to and propagated over the transmission lines, and radiated. The advantages of 10 this method are very clear; independence of the frequency and unlimited adaptation of the length of the coupling wires to the energy relations, and so on.

The practical embodiment of the invention is carried out in the following way. It 15 is appropriate to use separate coupling wires for transmission and reception. Lightning conductor cables which are insulated for a certain distance, are appropriately employed 20 for reception. The absorption of the incoming waves is carried out by having the receiving system withdraw energy from the lines. In case this withdrawal is not sufficient, a special resistance which also may be 25 arranged in the tuning means of the aerial, may be also used for this purpose. The tuning means are of course only devoted to the purpose to compensate the impedances which are required for the coupling.

30 In order to avoid the coupling wire of the transmitter influencing the neighboring aerial of the receiver, and consequently the receiver itself, an impedance can be connected in parallel to the tuning means of the aerial 35 of the receiver; this impedance is so dimensioned that it is very high for the receiving frequency but almost equal to zero for the transmitting frequency. The coupling wire of the transmitter is connected to earth across 40 the absorption resistance at a suitable distance from the high tension building as shown in Fig. 2.

In order to eliminate the disturbing influence of stationary oscillations on the propagation of the waves over the transmission 45 lines, suitable absorption resistances R can be connected across high tension condensers S to the ends of the lines one end of the line being shown in Fig. 3. The capacity of the 50 high tension transmission line with regard to the carrier frequencies may be compensated by a series connected inductance. The resistances of the high tension condensers and inductances which cause losses must be taken 55 into consideration with regard to the dimensioning of the absorption resistance. It is also possible to avoid a special absorption resistance by suitably dimensioning the loss resistances. In all cases in which the arrangements 60 of the high tension building represent a high capacitive shunt, the transmission lines can be choked from the transmission

line switches, whereby at the same time a disturbance of the conditions is avoided when the transmission line is earthed in the high tension building.

It is obvious that corresponding measures can be taken in case of pure coupling by means of condensers in order to avoid the 70 production of stationary oscillations.

Having described my invention, I claim:

1. The method of transferring radio frequency signals to and from a high tension transmission system which comprises transferring the radio frequency signal to or from the high tension line by capacitive coupling and preventing the development of stationary oscillations in said coupling by absorbing the progressive oscillations in resistance elements.

75 2. The combination of a high tension transmission line with a radio frequency signaling system comprising a high tension line, a coupling line, a radio frequency circuit and a resistance element in said coupling line 80 adapted to absorb progressive oscillations in said coupling line.

85 3. The combination in a radio frequency telephony system of a high tension transmission line and a radio frequency telephony 90 circuit, means for coupling said circuit to the line including resistance elements adapted to absorb progressive oscillations in said coupling means.

95 4. The combination in a radio frequency telephony system of a high tension transmission line and a radio frequency telephony circuit, means for coupling said circuit to said line, said means including a resistance element and a high frequency condenser connected to the end of said coupling means, said resistance being adapted to absorb the progressive oscillations in said coupling means.

100 5. In combination, a high tension power line, a radio frequency receiving system and means for coupling said system with said power line, said means comprising an antenna, means for tuning said antenna and means connected to said antenna for absorbing progressive oscillations therein.

105 110 6. In combination, a high tension power line, means for impressing signal currents of a given frequency on said line, a high frequency receiving system tuned to a different frequency and means for coupling said system with said power line and including an antenna, a resistance element connected to said antenna for absorbing stationary oscillations therein and means connected to said antenna whereby said receiving system is 115 rendered non-responsive to said first mentioned signal currents.

PAUL TATZ.
